TOOL RETAINER

Earl B. Lear, Detroit, Mich., assignor to Chicago
Pneumatic Tool Company, New York, N. Y.,
a corporation of New Jersey

Application January 26, 1935, Serial No. 3,555

4 Claims. (Cl. 121—32)

This invention relates to retainers for percussive tools and more particularly to a retainer or holder for preventing a drill steel from becoming detached from the front head of a rock drill in which it is supported.

Among the objects of the invention are: the provision of a steel holder which is of simplified construction and has a minimum number of parts; the employment of resilient means for absorbing shocks transmitted to the holder; reduction of wear on the front head of the drill; the provision of retainer locking means which need not be permanently secured to the front head; increased strength and durability of the holder; and convenience in attaching the holder to and removing it from the front head.

The invention may be embodied in a U-shaped retainer whose arms are mounted for longitudinal sliding movement within a pair of supporting trunnions which are mounted in the front head to rock with the retainer as a unit. An important feature of the invention resides in locking means cooperating with the trunnions for yieldingly holding the retainer in its normal operative position. The locking means is made effective by the resiliency of the retainer arms.

Other objects and features of the invention will appear more clearly from the following description taken in connection with the accompanying drawing and appended claims.

In the drawing, which illustrates one form of the invention:

Fig. 1 is a side elevational view showing the invention applied to a rock drill, fragmentary portions of the front head and drill steel being illustrated;

Fig. 2 is a sectional view as indicated by the arrows 2—2 in Fig. 1;

Fig. 3 is a bottom elevational view of the device illustrated in Fig. 1 with the drill steel shown in section;

Fig. 4 is a cross-section looking upwardly, as indicated by the arrows 4—4 in Fig. 1, certain parts being broken away; and

Fig. 5 is an end view of one of the trunnions (see arrows 5—5 in Fig. 4) showing also a fragmentary portion of the front head.

Referring to Figs. 1 and 2, a drill steel 10 is provided with a shoulder or abutment 11 engaging the lower end of a chuck 12 mounted in a bore 13 in the front head 14 of a rock drill cylinder. Shank 15 of the steel is of polygonal cross-section and has a sliding fit with the chuck. The upper end of the shank is adapted to receive blows from a piston extension 16. The structure

thus far described does not differ from that of conventional rock drills.

In accordance with the present invention, the front head, near its lower extremity, is provided with a transverse bore 17 whose axis lies in a plane at right angles to the axis of main bore 13. A cylindrical pin 19 extends across the last-mentioned bore at the midportion thereof. The front head is provided with a threaded opening 20 and a counterbore 21 cooperating with the respective ends of the pin or bolt 19 to secure the latter in fixed relation to the front head. While the bolt may be removed, if desired, removal thereof is not required in order to change tool holders, as will appear from the description which follows.

The tool holder or retainer 25, when viewed in side elevation is of U-shape having two vertical side arms 26, connected at their lower end to a yoke portion 27 which partially encircles the drill steel 10. Upstanding lugs 28 are provided on the yoke at opposite sides of an opening 29. These lugs are designed to resist the tendency of the retainer to swing away from the steel when the collar 11 strikes the yoke, as will be understood by those skilled in the art. A collar 30 is formed integrally on each of the arms 26 intermediate the ends thereof, and above the collar the arm comprises a reduced portion 31 preferably of cylindrical shape.

The reduced ends 31 of the retainer arms are slidably mounted and received within bores 32, each extending through the head 33 of a carrier member or trunnion 34. Each trunnion has a cylindrical portion extending into the bore 17 in the front head. Compression springs 35, surrounding the upper ends 31 of the retainer arms, engage the trunnion heads 33 and nuts 37 thereby to force the arms 26 upwardly and hold the collars 30 in contact with the trunnion heads.

The operative position of the retainer is shown in Fig. 2 with the yoke portion positioned directly below the collar 11 on the drill steel. The structure comprising the retainer, springs and trunnions may be swung as a unit about the axis of the trunnions in the direction of the arrow in Fig. 2, thereby to permit removal of the steel from the front head.

The invention includes means for yieldingly locking the retainer in the operative position shown in Fig. 2. The locking means comprises the pin 19 previously described, which cooperates with the inner end faces of the trunnions 34. As shown in Figs. 4 and 5 these end faces are provided with aligned grooves 40 adapted to fit

a portion of the cylindrical surface of the locking pin 19. In order to force the trunnions toward each other, the arms 26 of the retainer 25 are so constructed that they have a slight inward tension when connected to the front head. This tension acts on the trunnions to resist rocking movement away from normal position and tends to cause the trunnions to snap into alignment with the pin 19.

10 Lubrication of the trunnions is made possible by a port 41 communicating with the main bore 13 in the front head.

In operation, the piston 16 delivers a succession of blows to the steel whose collar 11 may 15 strike against the yoke 27 of the retainer 25. Springs 35 act as a shock absorber for the retainer by permitting it to yield in the direction of the blows. This not only minimizes wear on the front head but also prolongs the life of the 20 retainer. When it is desired to change steels, the retainer is swung in the direction of the arrow in Fig. 2. As the retainer swings it carries with it the trunnions and encounters resistance offered by the locking pin 19. This resistance, or 25 yieldable locking means, may be overcome by forcing the retainer and trunnions until the latter are cammed outwardly by the pin 19 and grooves 40.

The retainer may be replaced in a simple and 30 effective manner. As a first step, the nuts 37 are removed which frees the arms 35 to permit the retainer to drop. The trunnions are thereby set free and may also be replaced if desired.

It will be apparent to those skilled in the art 35 that various changes and adaptations of the illustrative embodiment of the invention may be resorted to without departing from the spirit of the invention. For example, the "front head" referred to in the specification and claims need 40 not necessarily be in one piece but may comprise several parts carried by the cylinder either in fixed relation or so connected relative thereto as to accomplish the results attained by the illustrative embodiment.

45 What is claimed is:

1. In combination with a front head and a collared drill steel supported therein, a retainer having a yoke portion adapted to receive blows transmitted to it by the collar and having arms 50 extending substantially parallel to the drill steel, said front head having a transverse bore extending in a plane at right angles to the axis of the drill steel, a pair of trunnions projecting into said bore from opposite ends thereof, said arms 55 being connected with said trunnions to swing with the latter about the axis of said bore, and means connected with the front head and engaging one or both trunnions to provide a yieldable lock for the retainer in one position of its swinging movement, said locking means comprising a cylindrical pin carried by the front head and extending 60 across said bore and engageable with a correspondingly-shaped groove formed in the end of one of the trunnions, and means for yieldingly 65 holding said trunnion in engagement with the pin.

2. In combination with a front head and a collared drill steel supported therein, a retainer having a yoke portion adapted to receive blows transmitted to it by the collar and having arms extending substantially parallel to the drill steel, 5 trunnions carried by said arms and projecting toward each other about a common axis, said front head having a transverse bore receiving the trunnions, a pin carried by the front head and positioned in said bore to engage the end faces of both trunnions, said end faces having cam surfaces engaging the pin, said arms being resilient and adapted to urge the trunnions toward each other, said cam surfaces being arranged to resist rotation of the trunnions away from a 10 normal position.

3. In combination with a front head and a collared drill steel supported therein, a retainer having a yoke portion adapted to receive blows transmitted to it by the collar and having arms 20 extending substantially parallel to the drill steel, trunnions carried by said arms and projecting toward each other about a common axis, said front head having a transverse bore receiving the trunnions, a pin carried by the front head 25 and positioned in said bore to engage the end faces of both trunnions, said end faces having cam surfaces engaging the pin, said arms being resilient and adapted to urge the trunnions toward each other, said cam surfaces being arranged to resist rotation of the trunnions away from a 30 normal position, said trunnions having openings in which the arms are received, said openings permitting limited longitudinal movement of the arms with respect to the trunnions, 35 and springs interposed between the trunnions and arms to resist such longitudinal movement in one direction.

4. In combination with a front head and a collared drill steel supported therein, a retainer having a yoke portion normally underlying the collar and having arms extending substantially 40 parallel to the drill steel on opposite sides of the front head, said front head having aligned transverse bores providing bearings, a pair of 45 axially aligned trunnions mounted to turn in said bearings and removable from the front head by movement away from each other, each trunnion having a bore in line with and receiving an arm of the retainer, whereby said retainer normally prevents removal of the trunnions from 50 the front head, said arms being shaped to fit the trunnion bores, removable members secured to the free ends of the arms, springs between 55 said members and the trunnions, and means 60 yieldingly resisting rocking movement of the trunnions and arms away from the normal position, said means comprising a cam surface formed on one of the trunnions and a complementary cam element secured to the front head, said retainer being resilient to force said trunnions toward each other and to hold said cam surface in engagement with said cam element.
